To all whom it may concern:

Be it known that I, PAUL T. Fig. 1 is a front perspective view of a combined clock casing and dial therefor showing my new design. Fig. 2 is a horizontal sectional view of the front wall surfaces including the clock dial taken through the center of the dial to indicate more clearly that the dial portion A is preferably set back slightly behind the glass cover B and that the surrounding surface C slopes away from the dial to meet the rear of the glass cover adjacent its edges.

I claim:

The ornamental design for a combined clock casing and dial therefor or similar article as shown and described.
